UNITED STATES PATENT OFFICE.

EDWIN M. ROSENBLUTH, OF PHILADELPHIA, PENNSYLVANIA.

DESIGN FOR A VEHICLE-NUMBER-PLATE SUPPORT.

41,899.

Specification for Design.

Patented Nov. 7, 1911.

Application filed June 12, 1911. Serial No. 632,784. Term of patent 14 years.

To all whom it may concern:

Be it known that I, EDWIN M. ROSENBLUTH, of Philadelphia, in the State of Pennsylvania, have invented a new, original, and ornamental Design for Vehicle-Number-Plate Supports, whereof the following is a specification, reference being had to the accompanying drawing.

The drawing shows a perspective view of said support.

I claim—

The ornamental design for a vehicle number plate support, as shown.

EDWIN M. ROSENBLUTH.

Witnesses:

ARTHUR E. PAIGE,
GERTRUDE N. R. MATTSON.
